DESIGN FOR A FIREPLACE MANTEL

Walter T. Prebis, Chicago, Ill.

Application January 23, 1946, Serial No. 125,870

Term of patent 3½ years

(Cl. D13—5)

To all whom it may concern:

Be it known that I, Walter T. Prebis, a citizen of the United States, residing at Chicago, in the county of Cook and State of Illinois, have invented a new, original, and ornamental Design for Fire Place Mantels, of which the following is a specification, reference being had to the accompanying drawing, forming part thereof.

Fig. 1 is a front elevational view of a fireplace mantel showing my new design;

Fig. 2 is a top plan view;

Fig. 3 is a side elevational view; and

Fig. 4 is a rear elevational view thereof.

I claim:

The ornamental design for a fire place mantel, substantially as shown.

WALTER T. PREBIS.
